(57) **CLAIM**

The ornamental design for a curved shower bar, as shown and described.

DESCRIPTION

FIG. 1 is a perspective view of a curved shower bar showing the new design;

FIG. 2 is a right side view thereof;

FIG. 3 is a left side view thereof;

FIG. 4 is a front elevational view thereof;

FIG. 5 is a back view thereof;

FIG. 6 is a bottom view thereof; and,

FIG. 7 is a top view thereof.

The broken lines showing a handheld shower head and a shower head are for the purpose of illustrating environment and form no part of the claimed design.
